NECK TAB FOR UNIFORM COLLAR

Maxine F. Spengler, Framingham, Mass., assignor to the United States of America as represented by the Secretary of the Army

Filed July 20, 1960, Ser. No. 61,514

Term of patent 14 years

(Cl. D3—8)

(Granted under Title 35, U.S. Code (1952), sec. 266)

FIG. 1.

The invention described herein, may be manufactured and used by or for the Government for governmental purposes, without the payment to me of any royalty thereon.

I claim:

The ornamental design for a neck tab for uniform collar, substantially as shown.
